TAPPET ADJUSTING TOOL

Alfred Gagne, Hartford, Conn.

Application June 2, 1938, Serial No. 211,399

3 Claims. (Cl. 81—3)

The present invention relates to hand tools and more particularly to a tappet valve adjustment tool.

An object of the present invention is to provide a tool to permit the ready and convenient adjustment of tappets and wherein the tool may be maintained in contact with the tappet throughout the period of adjustment.

A further object is a tool of this nature where-
10 in there is provided a screw driver bit for engaging the valve stem adjustment screw and a wrench for securing the adjustment screw jam nut and wherein the screw driver and wrench are rotatable independently of one another and are
15 both simultaneously and independently slidable within the holding member.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

25 In the accompanying drawing:

Figure 1 is a longitudinal sectional view with the tool positioned relative to a tappet;

Fig. 2 is a fragmentary view partially in section showing a detail of construction;

30 Fig. 3 is a fragmentary sectional view of the handle partially broken away to show the details of construction;

Fig. 4 is an end view looking from the bottom of the tool; and

35 Fig. 5 is a view of the wrench socket.

Referring to the drawing the operating handle 10 comprises an outer hollow wall member 11 closed at its upper end, and an inner hollow wall member 14 positioned centrally of the hollow wall member 11 and having its upper end 16 fixedly secured thereto for simultaneous rotation therewith. When so constructed, the inner and outer hollow wall members 14 and 11 are spaced apart and concentric relative to one another and define therebetween an outer bore 12 concentric with the hollow portion or inner bore 18 of the member 14.

The lower end of the member 14 is provided with oppositely disposed aligned slots 20 for receiving the upper rectangular end of a shank 22, the shank 22 being held therein by a pin 24 extending at right angles to the slots and passing through an elongated opening 26 in shank 22. The lower end of shank 22 terminates in a screw-engaging bit 28, and intermediate of the ends

there is provided a reduced portion 30 having an upwardly facing shoulder 32 at one end and a downwardly facing shoulder 34 at the other end which function as stops, as hereinafter described. The elongated slot 26 allows vertical movement of 5 shank 22 within slots 20, and a spring 36 carried within the bore 18 thereof normally urges the shank to lowermost position, as indicated in Figs. 1 and 2.

Surrounding shank 22 and preventing lateral 10 swinging thereof on pin 24 is a sleeve 40, the upper end of which extends into bore 12 of handle 10 and is so positioned by a positioning pin 42 which is threaded through the sleeve and is adapted to engage the shoulders 32 and 34 of 15 movable shank 22 and is normally urged into engagement with the lower shoulder 32 by a spring 44 intermediate of the upper end of sleeve 40 and the handle 10. The lower end of sleeve 40 is rectangular and provided with a downwardly 20 facing shoulder 46 against which is positioned a handle 48. Carried below the handle is a socket 50 removably secured to sleeve 40 by a screw plug 52.

The tool is shown in position for adjusting 25 a rockable tappet 60 having threaded at one end thereof an adjustment screw 62 which may be locked in position by a jam nut 64. In carrying out the adjustment, the operator may hold the handle 10 of the tool in one hand and with the 30 other hand back off the jam nut 64 by rotating the handle 48. If it is necessary to re-position the socket, the sleeve 40 may be raised against the tension of spring 44 to position the socket as shown in dotted lines, whereupon it may be turned 35 in the opposite direction and again positioned on the jam nut. When the jam nut has been released a sufficient amount, the handle 10 may be rotated to cause rotation of member 14 and the movable shank 22 to obtain a screw driver 40 action with the bit 28 engaged in the kerf of the adjustment screw 62. The adjustment may be made while the motor is running by simply pressing down on the handle 10, which will raise the shank 22 within the fixed shank and the sleeve 45 40 within the handle 10. By holding the handle in this position, the parts may reciprocate with the tappet, and by simultaneously rotating the handle 10 the adjustment screw may be set to give the proper clearance. When the proper 50 clearance has been obtained, the jam nut 64 may then be turned to secure screw 62 in adjusted position. It will likewise be seen that if the adjustment screw 62 is lowered down and into the nut 64, the bit 28 may still be brought into en- 55

gagement therewith by pressing down on the handle 10 due to the action of the spring 36 which will urge the shank downwardly into engagement with the pin 24. By providing a removable socket, 5 any desired size may be used with the one tool.

As many changes could be made in the above construction and many apparently widely different embodiments of this invention could be made without departing from the scope thereof, it is 10 intended that all matter contained in the above description or shown in the accompanying drawing shall be interpreted as illustrative and not in a limiting sense.

It is also to be understood that the language 15 used in the following claims is intended to cover all of the generic and specific features of the invention herein described and all statements of the scope of the invention which, as a matter of language, might be said to fall therebetween.

20 I claim as my invention:

1. A valve tappet adjusting tool comprising a handle having an open ended bore therein, a shank secured to the handle centrally of the bore, said shank having an opening therein and terminating in oppositely aligned slots, a screw engaging bit having a portion receivable in said slots, said portion having an elongated opening therethrough, a pin securing said bit in said shank and extending through said opening, spring 25 means normally urging said bit to its lowermost position, said bit also being provided with spaced apart downwardly and upwardly facing shoulders adjacent its lower end, a sleeve surrounding said bit and extending into the bore of said handle, 30 said sleeve having a stop adapted to be moved between the shoulders of said bit, and a spring mounted in said bore and normally urging said

sleeve downwardly to urge said stop into engagement with the upwardly facing shoulder of said bit, and a socket carried on the end of said sleeve.

2. A valve tappet adjusting tool comprising a manually operable handle having concentric inner and outer spaced apart hollow wall members closed at one end and defining inner and outer concentric bores at the other, a screw engaging bit receivable within said inner bore, cooperating means on said bit and inner wall member non-rotatably and reciprocably mounting said bit within said bore and limiting its movement therein, spring means normally urging said bit to its lowermost position, a socket wrench having a sleeve surrounding said bit and extending into 15 said outer bore, means reciprocably and rotatably holding said sleeve within said outer bore and spring means positioned within said outer bore and normally urging said sleeve to its outermost position.

3. A valve tappet adjusting tool comprising a handle having inner and outer concentric bores open at one end, a screw engaging bit having a portion receivable within said inner bore, means non-rotatably and slidably holding said bit within 25 said inner bore, spring means normally urging said bit to its lowermost position, a socket wrench having a sleeve surrounding said bit and having said sleeve extending into the outer bore, means engageable with said bit for rotatably and slidably holding said sleeve within said outer bore whereby said sleeve and bit may be moved longitudinally relative to one another and spring means positioned within said outer bore bearing against said handle and said sleeve, and normally urging said sleeve to its lowermost position.

ALFRED GAGNE.
